US00D940427S

(12) **United States Design Patent** (10) **Patent No.:** **US D940,427 S**
(45) **Date of Patent:** **** Jan. 4, 2022**

(54) **ELECTRIC CHAIN BLOCK**

(71) Applicant: **KITO CORPORATION**, Yamanashi (JP)

(72) Inventor: **Takayuki Kasai**, Yamanashi (JP)

(73) Assignee: **KITO CORPORATION**, Yamanashi (JP)

(**) Term: **15 Years**

(21) Appl. No.: **29/731,005**

(22) Filed: **Apr. 10, 2020**

(30) **Foreign Application Priority Data**

Oct. 11, 2019 (JP) 2019-022813

(51) **LOC (13) Cl.** **12-05**

(52) **U.S. Cl.**

USPC **D34/33**

(57) **CLAIM**

The ornamental design for an electric chain block, as shown and described.

DESCRIPTION

FIG. 1 is a rear perspective view of a first embodiment of an electric chain block;

FIG. 2 is a front perspective view of thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a rear perspective view of a second embodiment of an electric chain block;

FIG. 10 is a front perspective view of thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

1 Claim, 16 Drawing Sheets
